UNITED STATES PATENT OFFICE

HAROLD A. WADMAN, OF HARTFORD, CONNECTICUT, ASSIGNOR TO HARTFORD-EMPIRE COMPANY, OF HARTFORD, CONNECTICUT, A CORPORATION OF DELAWARE

APPARATUS AND METHOD FOR ANNEALING GLASSWARE

Application filed December 24, 1928. Serial No. 328,152.

This invention relates to a method and apparatus for annealing glassware, and it has particular relation to lehrs of the type embodying a tunnel through which a series of glass articles are transported and in which they are annealed by being subjected to a succession of varying temperature environments in a predetermined order and relation as to relieve stresses and strains existent in the ware.

In some installations it has been found that an excessive differential air pressure exists at opposite ends of the lehr tunnel, so as to cause a current of air from the outer atmosphere to flow through or into the tunnel from either the discharge end or the receiving end, and thus to disturb the desired order or relation of the thermal conditions within the tunnel, this action being known in the art as "drift". This air has a tendency to flow to some extent above and through the ware and to a relatively greater extent along the sides of the tunnel between the ware and the side walls, there being usually a greater distance between the outside articles and the sides of the tunnel than between adjacent articles. These side currents tend to cool the side-most articles to a greater extent than those nearer the center of the belt.

One of the objects of the present invention is, therefore, to eliminate the difficulties above referred to preferably by setting up a current of a gaseous medium such as air of a force, velocity, and direction such that the drift is counteracted to any desired extent.

Another object of the present invention is to provide in a tunnel lehr a counteracting current of a gaseous medium as above described which tends to cool the ware and which is directed in a generally downward direction onto the ware in the tunnel, there being also provision for controlling the volume of such gaseous medium.

A further object of the present invention is to direct the air as above described onto the ware in an even stream, the edges of which are spaced to some extent from the sides of the tunnel, so as not to accentuate the cooling of the side-most articles on the conveyor and to cool the articles nearer the center to about

the same extent as the side-most articles, the current of cooling medium supplied in this way serving effectually to counteract the drift through the tunnel.

Other objects and advantages of the present invention will be apparent from a reading of the following specification and subjoined claims when taken in connection with the accompanying drawings, in which:

Fig. 1 is a central vertical section through a lehr embodying my invention;

Fig. 2 is a transverse section of such a lehr taken substantially on the line 2—2 in Fig. 1;

Fig. 3 is a fragmentary section taken substantially on the line 3—3 in Fig. 2;

Fig. 4 is a fragmentary elevation showing the adjusting means for the nozzle as seen from the right hand side of Fig. 2; and

Fig. 5 is a central vertical section substantially similar to Fig. 1, but showing a modified construction.

For purposes of illustration, I have shown my invention applied to a lehr of the general type shown and described in the patent to Mulholland No. 1,560,481, granted November 3, 1925.

Referring to the drawings, the invention is shown as being embodied in a lehr comprising a tunnel 1 supported upon pedestals 2. The articles of glassware to be annealed are transported through the tunnel by a conveyor 3 extending therethrough, the conveyor being supported directly upon the heated floor thereof and being preferably of an open work wire mesh fabric and driven by any means (not shown), for instance such means as are described in the patent above referred to.

One or more heating flues 4 extends longitudinally below the tunnel and are supplied with hot gases from any suitable source, as the firebox 5. Suitable air inlet orifices 6 are provided communicating with the flue or flues 4 and are provided with dampers 7 by which the ingress of air from the atmosphere may be controlled. The gaseous medium in the flue 4 is withdrawn therefrom through lateral saddle pipes shown in dotted lines at 8 and is directed to a wind box 9 from which it is withdrawn by a suitable suction 100

fan 10 driven by a motor 11, or by any other suitable means, such as the usual stack.

For providing for the cooling of the ware in the cooling portion of the tunnel and for controlling drift, I provide one or more nozzle members 12, two of which are shown in Figure 1. These members are shown more particularly in Fig. 2, and each comprises a closed end pipe section having an elongate 10 nozzle portion 13 which is radially disposed and which terminates short of the sides of the lehr, as shown at 14, for a purpose hereinafter to be described. The nozzle pipe 12 is shown as mounted in suitable bearing portions 15 and 16 formed in the tunnel walls and is adapted to be rotated with respect thereto. For rotating the nozzle 12, I provide a member 17 suitably secured thereto and provided with a handle 18 by which the nozzle 12 may be turned as desired, the member 17 being also provided with an index 19 cooperable with a scale 20, as shown in Fig. 4.

Cooling medium is supplied to the nozzle member 12 through the lateral duct or conduit 21 (Fig. 2), the supply being controlled by a suitable damper 22. The pipe 21 preferably leads from a suitable header 23 which in turn leads from a suitable source of a gaseous medium such as the blower 24 (Fig. 1), 30 which may be driven in any desired manner, as by an electric motor 25. While I have shown a blower communicating with the atmosphere and thus adapted to direct atmospheric air into the lehr tunnel, it is obvious 35 that any other gas, heated or not, may be used and such other gas may be forced into the tunnel by any suitable means.

By a suitable control of the angular position of the nozzle opening 13 by the handle 40 18 and a suitable setting of the dampers 22, the gaseous medium flowing into the tunnel may be controlled to set up counter currents or gas curtains of such direction, velocity and volume as to control the drift there- 45 through as desired. The control usually desired is that which counteracts the drift, so that there is no drift whatsoever through- out the hotter portions of the tunnel.

Inasmuch as a large proportion of the drift 50 through lehr tunnels is normally between the ware at the sides of the conveyor and the sides of the tunnel, due to the relatively larger space at this portion adjacent to the bottom of the tunnel than in any other place 55 across the belt and the articles of glassware at the sides of the belt are thus cooled faster than those nearer the center of the belt, I prefer to construct the nozzles 12 as shown 60 in Fig. 2, with the opening for the drift controlling fluid shorter than the width of the tunnel and being disposed centrally thereof, so that the cooling effect of the air will be directed onto the glassware where it is most 65 needed and the sidemost article will be cooled

at approximately the same rate as those nearer the center of the belt.

I have shown in Fig. 5 a construction generally similar to that shown in the other figures, but different in that the flue 4' in this figure does not extend to the exit end of the tunnel, but terminates a short distance beyond the mid-portion thereof, the same or similar methods and means being used to control the temperature in this flue as in the flue 4 above described and these means being given corresponding reference characters. The chief difference, however, is that in addition to providing nozzles 12 adjacent to the roof of the tunnel, I provide a similar 70 nozzle or nozzles 26 situated just below the conveyor belt and directed upwardly into the tunnel. In this way I am enabled to provide a current of air both downwardly and upwardly which will be effective both for cooling the ware and for counteracting drift through the tunnel. The nozzle 26 may be constructed similarly to the nozzles 12 above described and is supplied with cooling air or other gas as above described through a 80 branch pipe 27 from the header 23, the current of gas being controlled by a damper 28.

Thus it will be seen that I have provided a combined cooling and drift controlling means which may be applied to the usual type of 90 glassware annealing tunnel and which is effective to control the drift to any desired extent and simultaneously to cool the ware in the tunnel, there being provision for suitable adjustment for effecting either of the 95 two purposes substantially independently of the other.

While I have shown and described but two embodiments of my invention, I do not wish to be limited thereto, but merely by the scope 105 of the appended claims, which are construed as broadly as the state of the prior art permits.

I claim as my invention:

1. In a continuous tunnel lehr for annealing glassware, a combined cooling and drift controlling means, comprising a nozzle mounted in said tunnel in the cooling portion thereof, means to cause a flow of cooling medium through said nozzle, and means to adjust the angular position of said nozzle so that said cooling medium flows in a direction at a selected angle with the longitudinal axis of said tunnel.

2. In a continuous tunnel lehr for annealing glassware, a combined cooling and drift controlling means, comprising a plurality of elongate nozzles disposed at intervals along the cooling portion of said tunnel and extending transversely thereof for supplying a cooling medium to said tunnel, means to vary the position of said nozzles to vary the angular relation between the direction of movement of the cooling medium issuing 120

from said nozzles and the longitudinal axis of said tunnel.

3. In a continuous tunnel lehr for annealing glassware, a combined cooling and drift controlling means, comprising a nozzle disposed adjacent to and transversely of the roof of said tunnel in the cooling portion thereof and having an elongate outlet terminating short of each side of said tunnel, said nozzle being arranged to direct a cooling medium into the tunnel at an oblique angle to the longitudinal axis thereof, and means to supply a controllable amount of a cooling medium to said nozzle, whereby to counteract drift through the tunnel and to direct the cooling medium thereinto substantially evenly of the transverse area of the tunnel without causing excessive cooling of the ware adjacent to the sides thereof.

4. In a continuous tunnel lehr for annealing glassware, a combined cooling and drift controlling means, comprising a nozzle disposed adjacent to and transversely of the roof of said tunnel in the cooling portion thereof and having an elongate outlet terminating short of each side of said tunnel, means to adjust the angular position of said nozzle about its longitudinal axis to vary the direction of a stream of a cooling medium passing therefrom into said tunnel, and means to supply a controllable amount of a cooling medium to said nozzle, whereby the drift through said tunnel may be controlled, and whereby to direct the cooling medium thereinto substantially evenly of the transverse area of the tunnel without causing excessive cooling of the ware adjacent to the sides thereof.

5. A lehr for annealing glassware, comprising an elongate tunnel, means for moving articles of glassware therethrough, a muffle flue extending longitudinally beneath said tunnel from a point adjacent to the inlet end thereof toward the exit end, means for supplying hot gases to said flue to control the temperatures within said tunnel, means for cooling the ware in the tunnel including a transversely elongated nozzle positioned in the cooler portion thereof adjacent to the roof of the tunnel, means to adjust the position of said nozzle to vary the direction in which the cooling medium is blown into said tunnel, and means for controllably supplying a cooling medium to said nozzle.

6. A lehr for annealing glassware, comprising an elongate tunnel, means for moving articles of glassware therethrough, a muffle flue extending longitudinally beneath said tunnel from a point adjacent to the inlet end thereof toward the exit end, means for supplying hot gases to said flue, means disposed at intervals along said flue for controlling the temperatures therein, means for cooling the ware in the tunnel including a transversely elongated nozzle positioned in the cooler

portions thereof adjacent to the roof of the tunnel, means to adjust the position of said nozzle to vary the direction in which the cooling medium is blown into said tunnel, and means for controllably supplying a cooling medium to said nozzle.

7. A lehr for annealing glassware, comprising an elongate tunnel, means for moving articles of glassware therethrough, a muffle flue extending longitudinally beneath said tunnel from a point adjacent to the inlet end thereof toward the exit end, means for supplying hot gases to said flue, air inlet openings disposed at spaced intervals along said flue for controllably diluting the gases therein for controlling the temperatures along said flue and thus the temperatures of the ware in corresponding portions of said tunnel, means for cooling the ware in the tunnel including a plurality of transversely elongated nozzles positioned in the cooler portion thereof adjacent to the roof of the tunnel, said nozzles terminating short of the lateral sides of the tunnel, and means to adjust the angular positions of said nozzles to vary the directions in which the cooling medium is blown into the tunnel, and means for controllably supplying a cooling medium to said nozzles, whereby to control the drift through said tunnel and whereby also to prevent the excess cooling of the articles adjacent to the lateral sides of the tunnel.

8. The method of annealing glassware, which comprises passing articles to be annealed in a continuous procession through an elongate tunnel, controlling the temperatures of at least a part of the bottom wall of said tunnel to control the temperatures of the ware in corresponding parts of said tunnel, and blowing a stream of a cooling medium down onto the ware at an oblique angle with the longitudinal axis of the tunnel, controlling the angle at which said cooling medium is flowing, and controlling the volume of such cooling medium, whereby to control the drift through the tunnel and whereby also to prevent the excess cooling of the articles adjacent to the lateral side of the tunnel.

9. In a continuous tunnel lehr for annealing glassware, a combined cooling and drift controlling means comprising a plurality of transversely extending nozzles disposed adjacent to and at intervals longitudinally of the roof of said tunnel in the cooling portion thereof, each of said nozzles having an elongate outlet opening terminating short of each side of said tunnel, and means to cause a controllable flow of a cooling medium into said tunnel at an angle to the longitudinal axis thereof through the openings of each of said nozzles, whereby to direct the cooling medium thereinto substantially evenly of the transverse area of the tunnel without causing excessive cooling of the ware adjacent to the sides thereof.

10. A lehr for annealing glassware, comprising an elongate tunnel, an open-work conveying means for moving articles of glassware therethrough, means for supplying heat to a portion of the tunnel adjacent to the ware-entering end thereof, means for cooling the ware in a subsequent portion of the tunnel, the last named means including a transversely extending elongate nozzle positioned beneath the path of the ware on said conveying means arranged to project a wide, relatively thin film of a cooling medium upwardly through the interstices of said conveying means and between the articles of ware passing through said tunnel, and means for controlling the amount of such cooling air admitted into said tunnel.

11. A lehr for annealing glassware, comprising an elongate tunnel, an open-work conveying means for moving articles of glassware therethrough, means for supplying heat to the portion of said tunnel adjacent to the ware-entering end thereof, means for cooling the ware in a subsequent portion of said tunnel, including a plurality of transversely elongated nozzles positioned in the cooler portion thereof, at least one of which is positioned adjacent to the roof of said tunnel, and adapted to project a cooling medium downwardly thereinto, and at least one of which is positioned beneath the path of the ware on said conveying means and adapted to project a cooling medium upwardly through the interstices of said conveying means and between the articles of glassware, and means effective independently to adjust the amount of cooling medium flowing through the top and bottom nozzles.

Signed at Hartford, Connecticut, this 20th day of December, 1928.

HAROLD A. WADMAN.
